(57) **CLAIM**

The ornamental design for a cord end cover, as shown and described.

DESCRIPTION

FIG. 1 is a front elevation view of a cord end cover showing my new design;

FIG. 2 is a top plan view thereof;

FIG. 3 is a right-side elevation view thereof;

FIG. 4 is a left-side elevation view thereof;

FIG. 5 is a cross-sectional view thereof, taken along line 5—5 in FIG. 1;

FIG. 6 is a cross-sectional view thereof, taken along line 6—6 in FIG. 2;

FIG. 7 is a front elevation view of a male member of the cord end cover;

FIG. 8 is a top plan view thereof;

FIG. 9 is a right-side elevation view thereof;

FIG. 10 is a left-side view thereof;

FIG. 11 is a bottom plan view thereof;

FIG. 12 is a cross-sectional view thereof, taken along line 12—12 in FIG. 7;

FIG. 13 is a cross-sectional view thereof, taken along line 13—13 in FIG. 7;

FIG. 14 is a cross-sectional view thereof, taken along line 14—14 in FIG. 7;

FIG. 15 is a cross-sectional view thereof, taken along line 15—15 in FIG. 7;

FIG. 16 is a front elevation view of a female member of the cord end cover;

FIG. 17 is a top plan view thereof;

FIG. 18 is a right-side view thereof;

FIG. 19 is a left-side elevation view thereof;

FIG. 20 is a cross-sectional view thereof, taken along line 20—20 in FIG. 16;

FIG. 21 is a cross-sectional view thereof, taken along line 21—21 in FIG. 16; and,

FIG. 22 is a cross-sectional view thereof, taken along line 22—22 in FIG. 17.

The male and female members of the cord end cover are shown separately in FIGS. 7 through 22 for clarity of illustration.
